UNITED STATES PATENT OFFICE.

WALDO A. LOUD, OF SPRINGFIELD, MASSACHUSETTS.

LAWN-MOWER.

SPECIFICATION forming part of Letters Patent No. 410,366, dated September 3, 1889.

Application filed September 25, 1888. Serial No. 286,390. (No model.)

To all whom it may concern:

Be it known that I, WALDO A. LOUD, a citizen of the United States, residing at Springfield, in the county of Hampden and State of Massachusetts, have invented new and useful Improvements in Lawn-Mowers, of which the following is a specification.

This invention relates to improvements in lawn-mowers, many features thereof being especially applicable to the class of lawn-mowers particularly known as the "roller-mower;" and it consists in the various constructions and combinations of parts, all substantially as will hereinafter more fully appear, and be set forth in the claims.

Reference is to be had to the accompanying drawings, forming part of this specification, in which—

Figure 1 is a plan view of the present improved lawn-mower of the roller class, the handle thereof being shown as broken off. Fig. 1^a is a horizontal sectional view in detail, illustrating a construction to be herein-after referred to. Fig. 2 is a side elevation 25 of the lawn-mower. Fig. 3 is a face view of one of the forward trucks and its bearings, and Fig. 3^a is a view of the truck-washer. Fig. 4 is a section thereof on line 4 4. Fig. 5 is a plan view of the under side of the stationary 30 cutter-bar and blade, and Fig. 6 is a cross-sectional view of one of the blades of the rotating cutter and a portion of its holding-arm. Fig. 7 is a view of the inside of one of the cheek or side plates of the machine-frame, 35 showing the bearing therein of and for the shaft of the rotating cutter.

Two parallel side or cheek plates A A², braced by the rods *a* and *b*, constitute the frame and supporting parts of the machine. 40 A traction-roller C, comprising a number of traction-wheels *d*, is mounted on a shaft 20, having a bearing in the said cheek-plates, and inclosed within the one A thereof is a spur-gear 22, fixed on one end of said shaft. 45 The cutter-shaft 23, carrying the revolving shearing cutter-blades *f*, is located in advance of said traction-roller and has bearings *g* formed in and supported by said cheek-plates at their inner sides, said shaft at one end extending within the chambered body of the 50 one cheek-plate A and provided with a pinion

25, which engages therewith through any suitable pawl-and-ratchet device, so that on the said pinion being rotated in one direction by the gear 22 through the intermediate gear 55 26, also mounted in the chambered body of the cheek-plate A, the said cutter-shaft will be rapidly rotated, and yet all so that on the rotation of the pinion in the opposite direction through the running of the roller in the backward or reverse direction no rotation will be imparted to the cutter-shaft, as well known. The said chambered cheek-plate A is to be inclosed by a suitable plate screwed to the outer side thereof.

The trucks or rollers D D are supported in advance of the revolving cutter in vertical planes about coincident to those of the cheek-plates and outside of the ends of the cutter-blades, being held from the said cheek-plates 70 by the forwardly-projecting bracket-arms 27, which, by their inner ends, are to be attached to the sides of said cheek-plates, either rigidly or adjustably thereon. The rear brace-rod *a* extends between the upwardly-extending 75 projections 28 of the cheek-plates, each of said projections having an inwardly-extending hub 29 let in or chambered from its outer side, as at 30, and provided with a transverse bore 32, and the said brace-rod is, near 80 each end, formed of reduced diameter, as at 33, the outwardly-extending portions beyond the shoulders 34 being screw-threaded, and the said ends are entered within the bores of the cheek-piece extensions, with the said shoulders 85 34 brought to an abutment against the inner ends of the hubs 29, and nuts 35 are screwed onto the said reduced end portions of the brace-rod against the outer walls of the chamber 30, constraining the parts in their 90 rigid relations to constitute the frame, as aforesaid; and it will be observed that the end portions 33 of the said brace-rod extend outwardly beyond the said nut 35 and serve to form the pivotal studs on which the forward forked end portions 36 of the longitudinal handle F engage and to permit a swinging action thereof in vertical planes. The said forked end portions 36 of the longitudinal handle F are each at their inner extremities bifurcated to form a longitudinal slot 37 95 and to embrace each projecting stud 33, and

when the end portions of the forked handle are adjusted in place the latches 38, pivoted thereon, are swung down to also engage by the recesses 39 therein the said studs 33 and 5 prevent any endwise movement of the handle in relation to its pivotal line, but to permit of an up-and-down swing of the end portions of said handle from said pivot. The end portions of the handle-forks 36 are held against 10 spreading outwardly by the webs 40, formed on the cheek-piece projections, and located with their inner walls against the outer side and parallel with the line of swing of said forks. The downward swing of the said handle-bar is limited by the shoulders forming 15 abutments 41, against which the lower edges of said end portions 36 may come to a rest, and there is also a web having an abutment 42 formed on the said projections 28, and, as 20 shown, located below the pivotal point in the circular line of travel of each end of the fork below its said pivot, whereby, on swinging the handle by its outer end higher than its normal position for use, the said end 25 portions 36 of the said forks will bear against said abutments, and on a still further raising of the outer end of said handle the rear end of the machine-frame and the traction-roller may be bodily lifted from the 30 ground, the whole machine at such time resting on the forward trucks D D, and may be rolled thereon abruptly in a lateral direction to turn the machine around or change its course without tearing up or gouging out 35 the turf, as might occur under such movements of the machine when the same was in bearing on the ground by its forward trucks and also the wheels of the traction-roller.

The stationary cutter, consisting of the cutter-bar H and the cutter-blade 54, adjustably secured thereon, is located, as usual, below and rearward from the revolving cutter and is mounted in bearings formed in or supported on the cheek-plates, which are capable 45 of permitting the usual rocking adjustment of the said cutter-bar, so that its edge may be presented at the desired proximity to the circular travel of the revolving cutter. The stationary cutter-blade 54 is, as particularly 50 shown in Fig. 5, secured on its cutter-bar H by the set-screws 55, passing through the slots 56, and back of the rear edge of said blade set-screws 57 57 are entered with a screw engagement through lugs 58, formed on the said 55 bar H, and bear by their inner ends against the rear edge of the cutter-blade. By unloosening the set-screws 55 and turning the set-screws 57 the cutter-blade may be adjusted forward to compensate for any 60 grinding away thereof or of the blades of the revolving cutter, and may be, under the engagement of set-screws shown, set forward farther at one end portion than at the other. The revolving cutter-shaft is by each end 65 mounted in bearings on the inner sides of the cheek-plates, as particularly shown in Fig. 7, and which consist of the web 59, forming a

horizontal socket which comprises two semi-circular chambers 60 and 62, open to each other, one 62 however being somewhat 70 smaller than the other and forming by its semicircular wall one-half of the shaft-bearing, and there are opposing lateral extension-recesses 63 at the junction of the walls of the said semicircular recesses, as shown. 75 Within the larger semicircular chamber 60 is located a separable and substantially semi-annular bearing-block 64, having its inner concave surface, when in place, in continuation of the circular contour of the inner face 80 of said smaller chamber 62, the thickness of said block being insufficient to entirely fill the space of the larger chamber 60, and the said block terminates at each end in opposing and outwardly-extending lugs 65, which enter the 85 lateral chamber-recesses 63. Through the opposing walls of one of said recesses two set-screws 67 67 are passed, bearing by their inner ends on the opposite sides of one of the lugs 65, and the other lug bears by its one 90 side on one wall of the other of said recesses, a set-screw 68 passing through its opposite wall and against the lug. By the said construction of the bearing for each end of the cutter-shaft, by turning one of the pair of set-screws inwardly and the other one outwardly, 95 one end lug of the adjustable semi-annular bearing-block may be either raised or lowered, moving with the other end lug as its fulcrum, and the wear on the shaft may be compensated as found necessary by the described 100 adjustable bearings at either or both ends. Each spiral blade of the revolving cutter is formed in two lengthwise sections 69 and 70, the one 69, constituting the cutter-strip proper, 105 being made comparatively thin and of steel of a superior quality, while the backing-up section of the blade may be of a metal of inferior quality and of less expense, and the superposed sections 69 70 are, without being welded 110 by the rivets 72, passing through them and the holder-arms 73, extending radially from the hub, held together and upon the said holder-arm. The forward trucks D D are preferably of a less diameter than that of the 115 traction-roller and are to be of a comparatively narrow tread, and are shown as consisting of the central web body 75, having a narrow-tread rim 76, and at and from each side of such rim a series of ribs 77 77 extend 120 for short distances in lines parallel with the axis of the truck-wheel, and thus by the said open-work construction sufficient tractive surface is given to the so-formed wheels D as truck-rollers and yet without being of such 125 an amount as to materially crowd down the grass, and moreover it will be observed that the said trucks being in substantially the planes of the cheek-plates and outside of the swath to be made by the cutters they are of 130 a most advantageous character.

Each bracket-arm 27, rigidly supported from the cheek-plates, has at its outer end a laterally-projecting boss 78, of a length to extend

through the hub 79 of the truck. The axial hole in the truck-hub 79 is of a greater diameter than the outer diameter of the bracket-boss 78, and between them is interposed a 5 sleeve 80, its inner bore fitting over the boss and the outer periphery fitting within the hub; but it will be observed the inner periphery of the sleeve is eccentric with its outer periphery so that by the turning of 10 the sleeve the center of rotation of the truck may be raised or lowered and thus the trucks may be adjusted to maintain the machine level. The boss of the bracket is axially bored, and against the end of the 15 boss and of the sleeve is placed a washer 82, a screw 83 passing through the perforation thereof and projecting through the said bored boss and beyond the opposite face of the bracket on which the boss is integrally 20 formed, receiving a nut 84 for confining the parts in their described relations, and the sleeve, when adjusted, immovable on the boss. The said washer overlies the circular line of 25 contact between the sleeve and hole in the truck-hub, and, as will be seen in Figs. 3 and 4, prevents the entrance of dust therat into the duct 85, formed in the hub-hole parallel to its axis and leading to the annular oil-groove 86 in the inner periphery of the hub. 30 The washer has a hole 87 through it at the same distance from its center that the duct 85 in the hub is from the axis thereof, so that when the hole 87 and duct are coincident oil may be introduced through said hole to the 35 said duct.

What I claim as my invention is—

1. The combination, with the cheek-plates A A², provided with the chambered faces 30 and bored hubs 29, of the brace-rod a, shouldered near each end, its end portions outside of said shoulders being screw-threaded, and the said brace-rod disposed between said cheek-plates abutting by its shoulders against the inner ends of said hubs, its outer ends 45 passing outwardly through and beyond said hubs, and also the nuts which are screwed on

said ends of the brace-rod and disposed within the said chambered faces of the cheek-plates, the said ends of the projecting brace-rod forming pivotal studs for the engagement of the handle-forks, substantially as 50 shown and described.

2. In a lawn-mower having opposing cheek-plates, the combination, with the stationary cutter-bar and cutter-blade and the revolving 55 cutter and its shaft, of the cheek-plate bearings for the revolving cutter-shaft, each consisting of the web 59, surrounding the chamber, comprising two semicircles of different areas and the opposing laterally-extending recesses 63, the semi-annular bearing-block 64, having the end lugs 65, loosely disposed in the larger semicircular portion of the said chamber and in the said recesses 63, the set-screws 67 67, screwing through the 65 opposing walls of one of the said recesses and against one of the lugs 65, and a single set-screw 68, screwing through one wall of the other recess and against the top of the other of said lugs 65, substantially as shown and 70 described.

3. In a lawn-mower having opposing cheek-plates, the combination, with the truck-holder arms supported from said cheek-pieces, each provided with the hollow boss 78, of the truck 75 having the bore of its hub of greater diameter than that of the said boss and provided with the annular oil-groove 86 and the duct 85, leading thereto from the end of the hub, the bushing-sleeve fitting on said boss and 80 within said truck-hub, the inner and outer circular peripheries thereof being eccentric to each other, the washer covering the end of the boss, the sleeve, and truck-hub, and the bolt 83, passing through said boss and washer, 85 resting by its head against the outer face thereof, and the nut 84, all substantially as shown, and for the purposes described.

WALDO A. LOUD.
